SHEET COLLECTING AND FOLDING MECH-
ANISM FOR PRINTING PRESSESHoward M. Barber, Pawcatuck, Conn., assignor to
C. B. Cottrell & Sons Company, Westerly, R. I.,
a corporation of Delaware

Application February 28, 1940, Serial No. 321,199

20 Claims. (CL. 270—72)

The object of my invention is to provide a folder which, with slight changes, will be operable to handle either shorter or longer sheets. The folder includes selectively operable means for cutting shorter or longer sheets, in the present instance by almost severing the sheets from the web or associated webs. The folder also includes means for folding and delivering either the shorter or longer sheets. The folder also includes means selectively positioned to engage the leading ends of the shorter or longer sheets, and, when so desired, to collect the sheets before they are folded and delivered.

A practical embodiment of my invention is represented in the accompanying drawings, in which—

Figs. 1 and 1^a represent a vertical longitudinal section through the folder, showing the operative elements arranged to cut, collect, fold and deliver the longer sheets;

Fig. 2 represents a similar view showing the operative elements arranged to cut, collect, fold and deliver the shorter sheets;

Figs. 3 and 3^a represent a vertical longitudinal section showing the gears and cams for operating the several elements; and

Fig. 4 represents a modified form of impaling pin holder in which the set of impaling pins for engaging the longer sheets may be shifted to another position in the holder for engaging the shorter sheets.

The upper pair of rotary cutters 1, 2 of equal diameters are shown as provided with two knives 3 and two cutting blocks 4 arranged, when operating, to partially sever two shorter sheets or groups of sheets from the web or associated webs, each revolution of the said cutters.

The lower pair of rotary cutters, i. e. the cylinders 5, 6 are shown as provided, the cylinder 5 with two equally spaced knives 7 and the cylinder 6 with three equally spaced cutting blocks 8 arranged, when operating, to partially sever three longer sheets or groups of sheets from the web or associated webs, each revolution of the said cylinders. The cylinder 5 is shown as two-thirds the diameter of the cylinder 6 in this arrangement.

The cylinder 6 is also shown as provided with three equally spaced holders 9, each holder carrying a set of removable impaling pins 10 for engaging the leading ends of the longer sheets, and an adjacent set of removable impaling pins 11 for engaging the leading ends of the shorter sheets. When the longer sheets are to be handled the impaling pins 10 are removed as indi-

cated in Fig. 1 and when the shorter sheets are to be handled the impaling pins 10 are removed, as indicated in Fig. 2.

The rock shafts 12 of the impaling pin holders 9 are provided with arms 13 carrying rollers 14 arranged in position to be operated at the proper times by the pin releasing traveling cam 15. This cam 15 is carried on the gear 16 which is rotatably mounted on the shaft 17 of the cylinder 6 and meshes with the gear 18 fixedly mounted on the shaft 19 of the cylinder 5.

One of the cheek pieces 20 of each of the spring pressed knife blocks in the cylinder 5 coacts with the sets of impaling pins 10 on the cylinder 6, 15 when longer sheets are to be handled. This cylinder 5 is also provided with two equally spaced spring pressed blocks 21 for coaction with the sets of impaling pins 11 on the cylinder 6 when shorter sheets are to be handled.

The cylinder 6 is also shown as provided with three equally spaced tucking blades 22 carried by spring pressed holders 23 whose rock shafts 24 are provided with arms 25 which carry rollers 26 arranged in position to be operated by the traveling tucking cam 27 on the cam gear 16.

The cylinder 5 is shown as being provided with two equally spaced spring pressed folding jaws 28 arranged to coact with the tucking blades 22 carried by the cylinder 6 to fold the longer or shorter sheets, as the case may be, onto the cylinder 5. The movable elements of the folding jaws 28 are mounted on rock shafts 29 provided with arms 30 which carry rollers 31 in position to be operated at the proper times by the fixed cam 32 to take the folded sheets from the cylinder 6 and by the fixed cam 33 to transfer the sheets to the delivery cylinder 34.

The delivery cylinder 34 is shown as provided with three sets of equally spaced spring pressed grippers 35. The rock shafts 36 of these grippers 35 are provided with arms 37 which carry rollers 38 which are engaged by a fixed cam 39 for causing the grippers to take the folded sheets from the jaws 28 of the cylinder 5 and deliver them to a predetermined point, such as an end-less delivery carrier 39.

The web feeding means is herein shown as comprising upper and lower pairs of reels 40, 41 and 42, 43 respectively, the upper pair being located above the rotary cutters 1, 2 and the lower pair being located between the said cutters and the cylinders 5, 6.

To permit the unimpeded passage of the shorter sheets between the lower reels after the leading ends of the shorter sheets have been taken

by their sets of impaling pins 11 on the cylinder 6, the discs of the reel 42 are each divided into two members and provided with cut-away portions 44, which cut-away portions may, by the 5 relative rotative movement of one disc member, be brought into alignment or out of alignment, as may be desired, and there fastened by the bolt 45 which passes through the elongated concentric slot 46 in the other disc member.

10 Vertically disposed web guides 47, 48 extend downwardly from the upper pair of feed reels 40, 41 between the upper rotary cutters 1, 2 and from thence through the lower feed reels 42, 43 to the lower rotary cutters, i. e. the cylinders 5, 6.

The means which I have shown for driving the several operating elements is constructed, arranged and operated as follows:

A main driving gear 49 meshes with a gear 50 20 fast on the shaft 17 of the cylinder 6, which gear 50 is in turn meshed with a gear 51 fast on the shaft 19 of the cylinder 5. This gear 51 is two-thirds the diameter of the gear 50 and as the cylinder 5 is two-thirds the diameter of the 25 cylinder 6 these two cylinders will be driven at the same surface speed. A gear 52 fast on the shaft 19 meshes with a gear 53 fast on the shaft 54 of the delivery cylinder 34. As this gear 52 is two-thirds the diameter of the gear 53 and as 30 the cylinders 5 and 34 are of equal diameters, the cylinder 5 will travel one and one-half revolutions every revolution of the delivery cylinder 34.

An intermediate gear 55 meshes with the gear 50 and also with a gear 56 fast on the shaft 57 35 of the upper rotary cutter 2. This gear 56 has the same number of teeth as the gear 51 so that the upper pair of cutters make even revolutions with the cutting and folding cylinder 5. A gear 58 fast on the shaft 57 meshes with a gear 59 40 fast on the shaft 60 of the upper rotary cutter 1.

A change gear 61 is adapted to be placed in either of two positions according to whether longer or shorter sheets are to be cut.

When longer sheets are to be cut the change 45 gear 61 is moved into position to mesh with the gear 51 on the shaft 19 of the cylinder 5 as shown in Figs. 1 and 3. When shorter sheets are to be cut the change gear is moved into position to mesh with the upper cutter gear 59 as shown 50 in Fig. 2.

In both of these positions the change gear 61 meshes with a gear 62 fast on the shaft 63 of the lower web feed reel 42, which gear 62 also 55 meshes with a gear 64 on the shaft 65 of the other lower web feed reel 43. The shaft 63 is also provided with a bevel gear 66 which meshes with a bevel gear 67 on the lower end of a vertically disposed shaft 68, the upper end of which shaft is provided with a bevel gear 69 which 60 meshes with a bevel gear 70 on the shaft 71 of the upper web feed reel 40. This shaft 71 is provided with a gear 72 which meshes with a gear 73 on the shaft 74 of the other upper web feed reel 41.

65 A slitter 75 may be used to slit the folded product on the delivery cylinder 34, if so desired.

In operation:

When longer sheets are to be cut, collected, folded and delivered, the following steps are 70 taken: the knives 3 are removed from the upper rotary cutters 1, 2 and the sets of impaling pins 11 are removed from their holders 9 on the cylinder 6. The change gear 61 is placed in position to mesh with the gear 51 on the shaft 19 75 of the cylinder 5. The cut-away portions 44 of

the discs of the lower reel 42 are closed so that the web or associated webs may be fed by both pairs of reels to the lower rotary cutters, i. e. cylinders 5, 6. The intermediate gear 55 need not be disconnected because the removal of the knives 3 from the upper pair of rotary cutters 1, 2 renders them inoperable to cut the web or associated webs passing therethrough. The several elements are then in position so that the longer sheets may be almost severed by the cutters 7, collected on their impaling pins 10 and folded off by the tucking blades 22 to the folding jaws 28 on the cylinder 5 to be transferred thereby to the cylinder 34 and by it to the delivery carrier 39. In this arrangement of gearing 10 the cylinders 5, 6 and the upper and lower pairs of feed reels 40, 41 and 42, 43 are all driven at the surface speed of the web or associated webs.

When shorter sheets are to be cut, collected, folded and delivered, the following steps are 20 taken: the knives 3 are placed in position in their upper pair of rotary cutters 1, 2 and the change gear 61 is brought into position to mesh with the rotary cutter gear 59. The sets of impaling pins 11 are inserted into their holders 9 and the sets 25 of impaling pins 10 are removed from the said holders. The cut-away portions 44 in the discs of the reel 42 are brought into alignment so that after the leading ends of the sheets almost severed by the upper pair of rotary cutters 1, 2 are 30 engaged by the impaling pins 11, the tail ends of the sheets may be torn from the web or webs and drawn freely between the reels 42, 43. The knives 7 on the cylinder 5 need not be removed, as they will be inoperable because they will 35 contact with their blocks 8 on the cylinder 6 in the spaces between the tail ends of preceding shorter sheets and the leading ends of the next succeeding shorter sheets. In this arrangement of gearing the upper and lower pairs of feed reels 40, 41 40 and 42, 43 and the upper pair of cutters 1, 2 are run at the surface speed of the web or associated webs and the cylinders 5, 6 at a slightly higher surface speed. To prevent the impaling pins 11 from stripping through the leading ends of the 45 shorter sheets the strain of tearing the sheets apart is taken by the spring pressed blocks 21 which pinch the sheets against the surface of the cylinder 6 as the impaling pins engage the sheets.

When it is desired to run a non-collected product of either longer or shorter sheets it is only necessary to disconnect the gear 18 from its shaft 19 and lock it against rotary movement by any well known or approved means, not shown herein, thus holding the impaling pin releasing cam 15 and the tucking blade operating cam 27 stationary.

In Fig. 4 a modified form of holder 9* is 60 shown, so that a common set of impaling pins, for example the impaling pins 10*, may be shifted for engaging either the longer or the shorter sheets.

It will be noted that a folder is provided which 65 may be quickly and easily adapted to handle longer or shorter sheets of predetermined lengths.

It will be noted that in this folder there is no adjustment necessary of the folding and delivery 70 mechanisms when changing from one length of sheets to another. The only change necessary is the silencing of one of the pairs of cutters and the changing in position of the impaling pins so that the sheets will be impaled in a pre- 75

determined relation to the folding blades and jaws and the delivery grippers.

It is evident that various changes may be resorted to in the construction, form and arrangement of the several parts without departing from the spirit and scope of my invention, and hence I do not intend to be limited to the particular embodiment herein shown and described, but what I claim is:

10. 1. In combination, web forwarding means, selectively operable means for cutting shorter or longer sheets, selectively positioned means for engaging the shorter or the longer sheets, and a common delivery for either the shorter or the longer sheets.

2. In combination, web forwarding means, two selectively operable pairs of rotary cutters for cutting shorter or longer sheets, selectively positioned means for engaging the shorter or the longer sheets, and a common delivery for either the shorter or the longer sheets.

3. In combination, web forwarding means, selectively operable means for cutting shorter or longer sheets, selectively positioned means for engaging and collecting the shorter or the longer sheets, and a common delivery for either the shorter or the longer sheets.

4. In combination, web forwarding means, two selectively operable pairs of rotary cutters for cutting shorter or longer sheets, selectively positioned means for engaging and collecting the shorter or the longer sheets, and a common delivery for either the shorter or the longer sheets.

5. In combination, web forwarding means, selectively operable means for cutting shorter or longer sheets, selectively positioned means for engaging the shorter or the longer sheets, a common means for folding either the shorter or the longer sheets, and a common delivery for either the shorter or the longer sheets.

6. In combination, web forwarding means, two selectively operable pairs of rotary cutters for cutting shorter or longer sheets, selectively positioned means for engaging the shorter or the longer sheets, a common means for folding either the shorter or the longer sheets, and a common delivery for either the shorter or the longer sheets.

7. In combination, web forwarding means, selectively operable means for cutting shorter or longer sheets, selectively positioned means for engaging and collecting the shorter or the longer sheets, a common means for folding either the shorter or the longer sheets, and a common delivery for either the shorter or the longer sheets.

8. In combination, web forwarding means, two selectively operable pairs of rotary cutters for cutting shorter or longer sheets, selectively positioned means for engaging and collecting the shorter or the longer sheets, a common means for folding either the shorter or the longer sheets, and a common delivery for either the shorter or the longer sheets.

9. In combination, web forwarding means, upper and lower selectively operable pairs of rotary cutters, means for causing the upper pair to cut shorter sheets or the lower pair to cut longer sheets, selectively positioned means for engaging the shorter or the longer sheets, and a common delivery for either the shorter or the longer sheets.

10. In combination, web forwarding means, upper and lower selectively operable pairs of rotary cutters, means for causing the upper pair to cut shorter sheets or the lower pair to cut

longer sheets, selectively positioned means for engaging and collecting the shorter or the longer sheets, and a common delivery for either the shorter or the longer sheets.

11. In combination, web forwarding means, upper and lower selectively operable pairs of rotary cutters, means for causing the upper pair to cut shorter sheets or the lower pair to cut longer sheets, selectively positioned means for engaging the shorter or the longer sheets, a common means for folding the shorter or the longer sheets, and a common delivery for either the shorter or the longer sheets.

12. In combination, web forwarding means, upper and lower selectively operable pairs of rotary cutters, means for causing the upper pair to cut shorter sheets or the lower pair to cut longer sheets, selectively positioned means for engaging and collecting the shorter or the longer sheets, a common means for folding the shorter or the longer sheets, and a common delivery for either the shorter or the longer sheets.

13. In combination, web forwarding means, an upper pair of rotary cutters provided with coacting cutting elements for partially severing shorter sheets, and a lower pair of rotary cutters provided with coacting cutting elements for partially severing longer sheets, the cutting elements of either pair of cutters being rendered operative according to the length of sheets to be cut, one of the lower pair of cutters being provided with sheet engaging devices for use with the shorter sheets and other sheet engaging devices for use with the longer sheets, either of said sheet engaging devices being rendered operative according to the length of sheets to be handled.

14. In combination, web forwarding means, an upper pair of rotary cutters provided with coacting cutting elements for partially severing shorter sheets, a lower pair of rotary cutters provided with coacting cutting elements for partially severing longer sheets, the cutting elements of either pair of cutters being rendered operative according to the length of sheets to be cut, one of the lower pair of cutters being provided with sheet engaging devices for use with the shorter sheets and other sheet engaging devices for use with the longer sheets, either of said sheet engaging devices being rendered operative according to the length of sheets to be handled, said lower pair of cutters being also provided with coacting folding devices for use with either the longer or shorter sheets.

15. In combination, web forwarding means, an upper pair of rotary cutters provided with coacting elements for partially severing shorter sheets, a lower pair of rotary cutters provided with coacting elements for partially severing longer sheets, the cutting elements of either pair of cutters being rendered operative according to the length of sheets to be cut, one of the lower pair of cutters being provided with sheet engaging devices for use with the shorter sheets and other sheet engaging devices for use with the longer sheets, either of said sheet engaging devices being rendered operative according to the length of sheets to be handled, said lower pair of cutters being also provided with coacting folding devices for use with either the longer or shorter sheets, and a delivery cylinder coacting with one of said lower pair of cutters.

16. In a folder, upper and lower pairs of rotary web feeders, upper and lower pairs of selectively operable rotary cutters for cutting shorter or longer sheets respectively, means for driving the

lower pair of cutters at a predetermined speed, and change speed means for driving the web feeders at the surface speed of the lower pair of rotary cutters when longer sheets are to be cut or at a lower surface speed when shorter sheets are to be cut.

17. In a folder, upper and lower pairs of rotary web feeders, upper and lower pairs of selectively operable rotary cutters for cutting shorter or longer sheets respectively, means for driving the lower pair of cutters at a predetermined speed, and change speed means including a change gear for driving the web feeders at the surface speed of the lower pair of rotary cutters when longer sheets are to be cut or at a lower surface speed when shorter sheets are to be cut.

18. In a folder, upper and lower pairs of rotary web feeders, upper and lower pairs of selectively operable rotary cutters for cutting shorter or longer sheets respectively, driving means including upper and lower pairs of operatively connected feeder gears, upper and lower pairs of operatively

connected rotary cutter gears, and a change gear operatively connected to the feeder gears and adapted to be operatively connected either to the upper pair of cutter gears or the lower pair of cutter gears.

19. In a folder, two selectively operable pairs of rotary cutters for cutting shorter or longer sheets respectively, selectively positioned sheet engaging devices for collecting either the shorter or the longer sheets, means for folding the collected sheets, and separate traveling cams for operating the sheet collecting and folding devices.

20. In a folder, two selectively operable pairs of rotary cutters for cutting shorter or longer sheets respectively, selectively positioned sheet engaging devices for collecting either the shorter or the longer sheets, means for folding the collected sheets, separate traveling cams for operating the sheet collecting and folding devices, and means for stopping the movement of the said cams when uncollected sheets are to be folded.

HOWARD M. BARBER.
